CLARENCE B. OVERLY, OF DETROIT, MICHIGAN, ASSIGNOR, BY MESNE ASSIGNMENTS, TO CLAYTON & LAMBERT MANUFACTURING COMPANY, OF DETROIT, MICHIGAN, A CORPORATION OF DELAWARE

BURNER STRUCTURE

Application filed March 15, 1929. Serial No. 347,333.

This invention relates to burner structure, and has to do particularly with liquid fuel burner structure of the type wherein the vaporized fuel from the generator is utilized to accelerate the starting operation.

The use of vaporized fuel initially ejected from the generator to assist in accelerating the starting of liquid fuel burners has recently been developed and burner structures embodying this principle are well illustrated in the pending applications of Charles F. Lambert Nos. 237,701 and 240,961, filed December 5 and 19, 1927, respectively. The structures referred to utilized a stationary generating tube, a stationary priming cup and a movable blast reflector for deflecting vaporized fuel, initially issuing from the stationary generator, downwardly and backwardly over the priming cup and against the generator. Such structures have been very satisfactory and are now in commercial use, but such structures are open to the objection that an opening is required between the priming cup and the space in front of the generating tube with the result that there sometimes is a tendency of the flames from the auxiliary burner for the generating tube to be drawn through such opening and thus cause pre-ignition of the gases issuing from the generating tube.

It is the object of the present invention to provide blast deflectors for use in starting liquid fuel burners of the type described in the above mentioned application, but which are also provided with an additional means for positively preventing the drawing in of any outside flames into the mixing chamber or the space between the generator tube and the mixing tube.

More specifically the present invention contemplates the provision of burner structure having a stationary generator tube, a stationary priming cup positioned beneath the generating tube, a partition plate at the end of said tube and having an opening for permitting the deflection of a blast of flame backwardly against the generating tube and a pivoted deflector member having an extension thereon, said extension being so arranged and said member being so pivoted

that when said deflector is in starting position, the vaporizing fuel and flames will be deflected rearwardly through said opening in the partition plate but that when the deflector member is moved to one side to permit normal operation, said extension will be automatically moved to close said opening in the partition plate.

In the drawings:

Fig. 1 is a plan view of a liquid fuel burner of the firepot type and illustrating the general arrangement of generator tube, priming cup, and auxiliary burner used therewith.

Fig. 2 is a vertical section taken on line 2—2 of Fig. 1 and showing in particular the relative positioning of the generator tube, the auxiliary burner, the priming cup and the deflector member when in a normal deflecting position.

Fig. 3 is an enlarged fragmentary side elevation of the operating parts of the firepot adjacent the end of the generator tube.

Fig. 4 is a vertical longitudinal section taken through the structure shown in Fig. 3 and illustrating my novel deflecting member in normal deflecting position.

Fig. 5 is a sectional view similar to Fig. 4 but showing the deflector moved out of position after the starting operation and also showing the novel manner of utilizing the extension of the deflector to close the space beneath the generating tube.

Fig. 6 is a sectional plan view of a modified structure showing the blast deflector mounted on a vertical pivot, the deflector in this figure being shown in a normally inoperative position, while the extension thereof is positioned to close the space beneath the generating tube.

Fig. 7 is a view similar to Fig. 6 but showing the deflector member moved to a normal starting position with the extension thereof positioned to permit passage of the flames through the partition opening.

Fig. 8 is a sectional view taken of line 8—8 of Fig. 6 and showing the deflector extension fitting in the opening in the partition plate.

Fig. 9 is a sectional view taken on line 9—9 of Fig. 7 and showing the extension moved

to one side to uncover the opening in the partition plate.

In illustrating the present invention, I have shown the same as embodied in a firepot, but it will be understood that the invention is equally well adapted to torch structure or any other burner structure of similar design.

In the embodiment shown, the firepot preferably comprises an annular burner member 10 which is supplied with vaporized fuel by means of a suitable conduit 2. This conduit 2 terminates in a mixing chamber 3, the entrance of which is suitably spaced from the outlet of a generator tube 4.

15 The outlet end of the generator tube 4 is preferably supported by a suitable head which forms a part of a partition member 5. The space between the partition 5 and the entrance end of the mixing chamber 3 may be open or may be enclosed by means of a suitable housing 6.

20 A permanently positioned fuel pan 7 is located beneath the generator tube 4 and a branch conduit 7a is preferably positioned along the side of the generator tube as best shown in Figs. 1 and 2. The fuel pan or priming cup 6 serves to assist in initially starting the vaporization of the fuel in the tube and the auxiliary burner of the auxiliary conduit serves to maintain a vaporizing temperature. A blast deflector 8 is pivotally mounted within the space between the partition member 5 and the inlet of the mixing chamber 3 as best shown in Figs. 3, 4 and 5.

25 This deflector member is so shaped and so pivoted as at 9 that when in the position shown in Fig. 4 it will serve to deflect vaporized fuel issuing from the tube downwardly and backwardly against the generator tube 4. A suitable arm 10 is connected to the deflector member 8 and suitable lugs 11 and 12 serve to position such an arm in two positions whereby the deflector member may be held in two positions as shown in Figs. 4 and 5.

30 To permit the rearward deflection of the vaporized gases and flames, the partition plate 5 is provided with a suitable opening 13. The pivot point 9 for the deflector member 8 is positioned just beneath this opening 13 and the deflector member 8 is provided with an extension 14 which is so formed that, in the operative position of the blast deflector as shown in Fig. 4, it will permit the conducting of the liquid fuel to the priming cup, but that when the deflector 8 is moved to the position shown in Fig. 5 it will substantially close the opening 13 so as to positively prevent the drawing in of any flames from the burner 7a through the opening 13 and into the space adjacent the mixing chamber. The provision of this extension member as a part of the deflector member insures that the opening 13 will always be closed when the burner member is in normal operation, because it is

impossible to operate the main burner member unless the deflector is moved away from its normal deflecting position.

35 The operation of this device will be obvious. The liquid fuel is first allowed to flow through the generator tube 4 and a small quantity of the same is allowed to flow out through the outlet so as to strike the deflector and be conducted to the priming cup. After a small amount of liquid fuel has accumulated in the priming cup the valve in the inlet end of the generator tube is closed and the liquid fuel in the priming cup ignited. The open flames from the priming cup quickly heat the generator tube to vaporize the liquid fuel therein and this vaporized liquid fuel will be forced outwardly under the pressure against the deflector member 8. The shape of the deflector member will cause the vaporized fuel to be deflected backwardly over the surface of the liquid fuel in the priming cup and directly against the generating tube so as to accelerate the heating thereof and the starting of the generating apparatus. This blast of flame from the deflector will quickly heat up the generator tube with the result that when substantially all the gases are emitted from the generator tube, the tube will be hot enough for continued permanent operation at which time the lever 10 is moved to position the deflector 8 in the position shown in Fig. 5, whereby the vaporized gases will be conducted through the main manifold 2 to the auxiliary burner 7a and the main burner 1. The extension member or baffle 14 will sufficiently close the opening 13 to prevent the drawing in of any flames from the auxiliary burner.

40 In the modification shown in Figs. 6—9, a deflector member 15 is positioned to swing around a vertical axis 16 so as to permit the positioning of the deflector in front of the generator tube as shown in Fig. 7 or to one side of the axis of the tube as shown in Fig. 6. In this modification the inlet of the mixing chamber may be designated as at 17 and an extension of the priming cup 7 is formed as at 18, whereby in case the deflector member 15 should be accidentally out of position, the liquid fluid will be conducted back to the priming cup by means of such extension 18.

45 In this modification the deflector 15 is provided with an extension 19 which is adapted to close the opening 13 in the partition plate 5. Figs. 8, and 9 show the extension 19 in position to close the opening in the partition and in open position to permit the rearward direction of the flames.

50 What I claim is:

1. A liquid fuel burner comprising a generating member, a burner positioned adjacent the outlet end of the generating member, for normally maintaining the same at vapor

ization temperature, a pivotally mounted deflector member adapted to be positioned in front of the generator member for deflecting the vaporized gases initially issuing therefrom backwardly against said generator to accelerate the starting thereof, and means adapted to be positioned adjacent the end of a generating tube during normal operation, tending to prevent the drawing of any flames from the said burner into the space in front of the generating tube.

2. A liquid fuel burner comprising a stationary generator tube, a partition plate having an opening for receiving the end of said tube, an auxiliary burner positioned along side of the generator tube, a mixing chamber spaced from the end of the generator tube and said plate, a pivotally mounted blast deflector movable in the space between the generating tube and mixing chamber, an opening in said partition plate for receiving the blast from said deflector and a member connected to said deflector and adapted in one position of the deflector to close said last named opening and in another position of the deflector to be moved away from said opening.

3. A liquid fuel burner comprising a generating tube, a partition member having an opening for receiving the end of the tube, a stationary priming pan positioned beneath the generating tube, an auxiliary burner positioned adjacent to said tube, a deflector member movable to a position in front of said generating tube to act as a blast deflector and movable to a position away from said generating tube to permit conducting of vaporized fuel to the burner, and opening in said partition member serving as a passageway for the blast from said deflector and means actuated by the movement of said deflector member to open or close said opening.

4. A liquid fuel burner comprising a stationary generating tube, an auxiliary burner positioned along side thereof, a stationary priming cup positioned beneath the generating tube, a deflector member pivotally mounted to be moved to a position in front of the generator tube or to one side of the axis thereof and an extension formed integrally with said deflector member and acting, when said deflector is moved away from said axis, as a baffle to restrict the flames from said auxiliary burner to the space to the rear of the end of the generating tube.

5. A liquid fuel burner comprising a stationary generating tube, a partition plate having an opening cooperating with the end of said tube, an auxiliary burner positioned along one side of said tube, a stationary priming cup positioned beneath said tube, an opening in said partition plate beneath the end of said generator tube, a blast deflector pivotally mounted substantially in the plane of said partition plate and movable to a position

in front of or to one side of said generator, and an extension member so positioned relative to said pivot point that when said deflector member is moved to one position, said extension is moved to a position to close said opening. 70

In testimony whereof I affix my signature.
CLARENCE B. OVERLY.
